(No Model.)

W. CORLISS.

BURGLAR PROOF SAFE.

No. 271,314.

Patented Jan. 30, 1883.

UNITED STATES PATENT OFFICE.

WILLIAM CORLISS, OF PROVIDENCE, RHODE ISLAND.

BURGLAR-PROOF SAFE.

SPECIFICATION forming part of Letters Patent No. 271,314, dated January 30, 1883.

Application filed June 27, 1882. (No model.)

To all whom it may concern:

Be it known that I, WILLIAM CORLISS, of the city and county of Providence, in the State of Rhode Island, have invented certain new and useful Improvements in Burglar-Proof Safes; and I do hereby declare that the following is a full, clear, and exact description thereof.

In an application for patent for burglar-proof safes filed by me December 30, 1881, and allowed January 4, 1882, I have described a means of strengthening spherical or spheroidal safes of cast metal, constructed as set forth in a patent granted to me March 25, 1873, No. 137,061, by inclosing in the casting a basket formed of bars of wrought-iron or other suitable tough but relatively soft metal. In that safe the shell or main part is formed of two parts joined in a plane passing through or near the center of the entire structure. I have now worked out another construction of spheroidal safe, in which the entire main body of the safe is formed of one single shell or casting, with a suitable small opening or hole for the door. The shape of this new shell is spherical, with the portions near the top and bottom flattened. In one of these flattened portions is formed a hole of sufficient diameter to permit the introduction of the inwardly-opening door, which hole is subsequently closed by means of a head screwed in firmly. I prefer for facility of manufacture to make such opening thus closed by a screwed head not only at the top, but also at the bottom.

It will be observed that in the old form of safe as set forth in my above-mentioned patent the ring-shaped joint formed in a plane necessitated a large increase of metal at that point in order to prevent the possibility of splitting or rending it apart by means of wedges. In my present improved safe this joint is avoided altogether, and I am able to produce a safe of more uniform thickness and of increased strength. The joints of these openings have a cylindrical form, and, being in a nearly flat body of sufficient thickness, this construction precludes all effective use of wedges. The general construction of this planet safe is made the subject-matter of a separate application for patent.

The object of the present invention is to adapt the method of strengthening the casting or shell of the safe by means of a basket

to this planet safe. This is accomplished by using a single basket of spherical or approximately spherical shape. Any attempt to rend apart or split the safe on any line, in whatsoever plane laid through the structure, is strongly resisted by the tough material of the basket, in addition to the great resistance offered by the casting itself. The several rods composing such basket are preferably arranged in a manner corresponding to the parallels and meridians of a planet. The continuity of the meridians and of those parallels which have the largest diameters is interrupted by the presence of the holes at the poles, and of the one hole for the door at the equator of the structure; but by reason of the firm union of the basket with the cast-iron in which it is embedded such openings have no weakening effect on the basket. The holes are comparatively small with relation to the respective curvatures of the body of the safe, so that they form practically round holes in a nearly-flat surface. The surrounding metal is a continuous ring inclosing the head, and of a strength sufficient to resist all wedging forces. By reason of this condition a separation from the main body of the parts inserted to close said holes cannot be effected by wedging or any analogous process. The bars composing the basket are all properly bent before being put together, and in forming the basket the bars may simply be connected with each other by means of small wires, so as to hold them in their proper relative position while the metal is being cast around them; but in the most complete form of my invention I use three stout hoops to inclose the three openings in the safe-body, and I frame the entire basket upon these hoops, using them as a base for the operation. They also serve to firmly hold the parts together until finally confined by the metal cast around the basket. The hoops contribute great strength to the structure.

The accompanying drawings form a part of this specification, and represent what I consider the best means of carrying out the invention.

Figure 1 is a perspective view of the hoops encircling the three openings in their proper relative positions. Fig. 2 is a perspective view of a basket constructed according to my invention. Fig. 3 is a section of a part of a safe-body constructed according to my invention.

Fig. 4 is a central horizontal section of about one-half of my basket, and Fig. 5 is a central vertical section thereof. Figs. 1 and 2 are both on one scale. Figs. 4 and 5 are on a larger scale, and Fig. 3 is on a still larger scale.

Similar letters of reference indicate the same parts in all the figures.

A is a stout hoop, of wrought-iron or other suitable metal.

10 B are parallel circles of bar-iron, preferably of round section. Those parallels which are between the horizontal planes passing through the top and bottom portions of the hoop A are cut open, and their ends are bent outward and 15 secured in the holes in the hoop A.

CC are hoops, of iron or other suitable metal, at the top and bottom or at the poles of the structure.

10 D are iron bars bent in the shape of a half-circle, but somewhat shorter. These bars are applied meridianwise to the outside of the structure formed by the parallels, and their ends are secured in holes formed for the purpose in the rings C. D' are shorter bent bars, 25 also applied meridianwise between the bars D, but not reaching entirely up and down to the rings C, so that the distance between the meridional bars over the whole surface is more nearly uniform than it would be if all the meridional bars were of full length. The parts 30 B—principally those which form complete circles—and the parts D' may be connected with the other parts, B and D, and with each other by means of wires twisted around them, or in 35 any other appropriate manner.

The basket thus formed is introduced in the mold in which the safe-body is to be cast, and the melted metal, when poured into the mold, flows around all the parts of said basket and 40 strongly unites therewith. In the drawings, E represents this cast metal.

In my above-mentioned application for patent, allowed January 4, 1882, I have given in detail a description of the means employed for 45 successfully effecting an intimate union of the cast metal with the wrought-iron basket-work

embedded therein. The same means may be employed here.

Modifications may be made in the details without departing from the principle of the 50 invention.

The parts D' may be omitted.

The number of parts B D D' may be varied within wide limits, according to the dimensions of the safe to be constructed.

55 The castings for the door and for the heads to close the openings at the poles may be provided with basket-work, or may be simple castings; but I prefer the former construction, as making the entire safe more proof against the 60 action of drills.

I claim as my invention—

1. A spherical or spheroidal basket having one or more openings of relatively small diameter, composed of parallel rings B and meridional rings or sections of rings D, and adapted 65 to serve in a spherical or spheroidal safe-body E, cast in one piece, substantially as and for the purposes herein specified.

2. A spherical or spheroidal basket having 70 one or more openings of relatively small diameter, composed of parallel rings B and meridional sections of rings D and shorter sections D', interposed between the parts D, all combined and adapted to serve in a spherical safe- 75 body E, cast in one piece, substantially as and for the purposes herein specified.

3. In a burglar-proof safe, the basket having the rings A and CC, with a number of the parallels B and the meridians D fastened therein, 80 respectively, said rings serving as a base upon which to frame the entire structure, substantially as herein specified.

In testimony whereof I have hereunto set my hand, at Providence, Rhode Island, this 24th 85 day of June, 1882, in the presence of two subscribing witnesses.

WILLIAM CORLISS.
